LAPPING MACHINE

Herbert S. Indge and George E. Hulbert, Westboro, Mass., assignors to Norton Company, Worcester, Mass., a corporation of Massachusetts

Application April 9, 1936, Serial No. 73,547

12 Claims. (Cl. 51—118)

This invention relates to abrading machines, and more particularly to a lapping machine.

One object of this invention is to provide a simple, thoroughly practical lapping machine for simultaneously lapping a plurality of work pieces. Another object of this invention is to provide an improved lapping machine in which a new set of work pieces may be loaded ready for a lapping operation during the lapping of one set of work pieces. It is a further object of this invention to provide a work carrier having two sets of work holders, one set of which is in an operating position for a lapping operation while the other set is in a loading position.

15 It is a further object of this invention to provide a lapping machine in which the finished lapped pieces of work may be simultaneously and readily withdrawn from operative relation with the lapping wheels while a new set of work pieces is being simultaneously moved into lapping position relative thereto. It is another object of this invention to provide a fluid pressure mechanism to simultaneously move the lapping wheels toward and from each other. Further objects will 20 be in part obvious or in part pointed out hereinafter.

25 The invention accordingly consists in the features of construction, combinations of elements, and arrangements of parts, as will be exemplified in the structure to be hereinafter described, and the scope of the application of which will be indicated in the following claims.

In the accompanying drawings in which is shown one of various possible embodiments of the mechanical features of this invention,

30 Figure 1 is a front elevation of the improved lapping machine, having parts broken away and shown in section to more clearly show the operating construction;

35 Figure 2 is a cross sectional view through the lapping machine, taken approximately on the line 2—2 of Figure 1, having parts broken away to more clearly show the construction;

40 Figure 3 is a fragmentary sectional view, partly in elevation, of a portion of the cage and lapping wheels, on an enlarged scale, as shown in Figure 1;

45 Figure 4 is a fragmentary sectional view of the work carrying cage, taken approximately on the line 4—4 of Fig. 3, showing one pair of the work supporting members;

50 Figure 5 is a longitudinal sectional view, on an enlarged scale, of the main driving clutch;

55 Figure 6 is a sectional view, on an enlarged scale, through one of the cage driving members;

Figure 7 is a fragmentary detail view, on an enlarged scale, of the supporting plate for the cage driving pin, as shown in Figure 6; and

Figure 8 is a piping diagram of the fluid pressure system.

A lapping machine has been illustrated in the drawings having a base 10 which rotatably supports a pair of opposed relatively rotating wheels 11 and 12. The lapping wheels 11 and 12 are supported on spindles 13 and 14, respectively. 10 The spindle 13 is journaled in bearings 15 and 16 in the base 10. The lapping wheel spindle 14 is journaled in similar bearings (not shown). The construction of the head supporting the lapping wheel 12 is identical with the construction 15 shown in section (Fig. 1) for the lapping wheel 11, consequently only one of the heads has been illustrated in detail. The spindle 13 is provided with a driving pulley 18 which is connected by a plurality of V-belts 19 with a pulley 20 mounted 20 on the outer end of a rotatable driving shaft 21 which is rotatably supported in bearings (not shown) in the base 10.

The shaft 21 may be driven from any suitable source of power but for the sake of illustration, 25 an electric motor 25 has been provided and is mounted on a projecting bracket 26 on the base 10 of the machine.

The electric motor 25 is connected with a standard gear reduction unit, as indicated by the casing 37 to rotate a shaft 38. 30

The shaft 38 is connected by means of a suitable clutch 39 to rotate a shaft 40. The shaft 38 is provided with a fixed internal cone clutch member 41 which is arranged to be engaged by an external cone clutch member 42 which is slidably 35 keyed by a key 43 with the shaft 40. When the clutch member 42 is moved toward the left (Fig. 5) into engagement with the cone surface 41, the rotation of the shaft 38 is transmitted to rotate shaft 40.

The shaft 40 is provided with a gear 45 which is connected by a link chain 46 with a gear or sprocket 47 mounted on the shaft 21. The shaft 21 carries a gear 50 which meshes with a gear 51 mounted on a rotatable shaft 52 which 40 is rotatably supported in bearings (not shown) in the base 10. The shaft 52 is provided with a grooved pulley 53 which is connected by belts 54

45 with a grooved pulley 55 mounted on the outer end of the spindle 14 to rotate the lapping wheel 12. The lapping wheel 12 rotates in the opposite direction relative to the rotation of the lapping wheel 11 due to the gears 50 and 51 which form a driving connection between the shaft 21 and the shaft 52.

50 In order to facilitate manual operation of the 55

clutch 39 from the front of the machine, a manually operable clutch lever 60 is mounted on the outer end of a shaft 61 which is rotatably supported in bearings 62 and 63 in the base 10. The shaft 61 supports a yoked member 64 which engages a groove 65 in the clutch member 42 and serves to engage or disengage the clutch so as to start or stop the transmission of power from the motor 25.

10 The lapping wheel 11 is moved toward or from an operating position by means of a hydraulically actuated mechanism. The outer end of the lapping wheel mount is provided with a roller thrust bearing 70 which is supported in the lower 15 end of an arm 71 which is mounted on a conical portion 72 of a slidably mounted rod 73. A fluid pressure piston 74 is connected by means of a rod 75 with the slide rod 73. The piston 74 is slidably mounted within a cylinder 76. When fluid under 20 pressure is admitted through a pipe 77 into a cylinder chamber 78, the piston 74, the rod 73 and the arm 71 are moved toward the left (Fig. 1) to move the lapping wheel 11 toward the left. Similarly, when fluid under pressure is admitted 25 through pipe 79 into cylinder chamber 80, the piston 74 is moved toward the right to cause a corresponding movement of the lapping wheel 11 to separate the lapping wheel 11 from the lapping wheel 12.

30 The lapping wheel 12 is arranged for a similar fluid pressure movement, details of which have been illustrated diagrammatically in Fig. 8. The outer end of the mount for the lapping wheel 12 is connected by an arm 89 which is supported on 35 the end of a slide rod 85. A fluid pressure piston 100 is connected by means of a piston rod 101 with the slide rod 85. The piston 100 is slidably mounted within a cylinder 102. When fluid under pressure is admitted through a pipe 87 into a cylinder 40 chamber 103, the piston 100, the rod 85 and the arm 89 are moved toward the right (Figs. 1 and 8) to move the lapping wheel 12 toward the right. Similarly, when fluid under pressure is admitted 45 through pipe 88, into a cylinder chamber 104, the piston 100 is moved toward the left (Figs. 1 and 8) to cause a corresponding movement of the lapping wheel 12 to separate the wheel 12 from the lapping wheel 11.

It is desirable that the lapping wheels 11 and 12 50 be arranged so that they may be moved simultaneously toward and from the work piece to be lapped before and after the lapping operation. This is preferably accomplished by means of the fluid pressure system which comprises a reservoir 55 105 in the base of the machine. Fluid is pumped from the reservoir by means of a pump 106 and conveys fluid through a piston type reversing valve 107. The reversing valve 107 is operatively connected between the pump 106 and the pipes 77, 60 79, 87, 88, so as to simultaneously control the admission of fluid to the cylinders 76 and 102. When the reverse valve is in the position illustrated in Figure 8, fluid under pressure is simultaneously admitted through pipes 77 and 87 into 65 cylinder chambers 78 and 103 respectively to simultaneously move the lapping wheels 11 and 12 toward each other into operative engagement with the work piece to be lapped. During this movement, fluid is simultaneously exhausted 70 from the cylinder chambers 80 and 104 into the reservoir 105. When the valve 107 is shifted into its reverse position, the fluid under pressure from the pump 106 is passed simultaneously through pipes 79 and 88 into cylinder chambers 80 and 75 106, respectively, to cause a separating movement

between the lapping wheels 11 and 12 after the lapping operation has been completed.

A manual adjustment is provided for each of the lapping wheels 11 and 12 to adjust the lapping wheel into a proper position in setting up the machine for lapping a given work piece. A slidably mounted rod 90 is mounted in a portion 91 of the base 10 and extends through a hole in the arm 71. Adjustably spaced collars 92 and 93 are arranged on opposite sides of the arm 71 and are spaced therefrom to allow movement of the arm 71 without movement of the rod 90. By adjusting the position of the collars 92 and 93 on the rod 90, the extent of fluid pressure movement of the lapping wheel 11 may be varied, as desired. By adjusting the position of the rod 90 relative to the casing 91, the position of the movement of the lapping wheel 11 may be adjusted as desired. To facilitate adjustment of the rod 90, a rotatable screw 95 is supported in a bearing 96 in the frame 20 91 and the screw 95 is held against endwise movement by means of the bearing 96 and a manually operable hand wheel 97. The screw 95 is threaded into the end of the rod 90 so that when the hand wheel 97 is rotated in either direction, it transmits a corresponding rotary motion to the screw 95 to move the rod 90 endwise and thereby change the position of the arm 70 so as to vary the path of movement of the lapping wheel 11. A similar construction is provided for controlling the movement of the lapping wheel 12. A slidably mounted rod 98 is mounted in the housing 86 and is arranged to be adjusted longitudinally within the housing 86 by means of a manually operable hand wheel 99 which serves to permit adjustment of 30 the path of movement of the lapping wheel 12.

In order to produce the desired lapping operation to simultaneously lap or abrade the opposite parallel faces of a plurality of work pieces to be 40 lapped, a work carrying cage is provided which is arranged to support a plurality of work pieces for a simultaneous lapping action between the lapping wheels 11 and 12. The cage member is preferably arranged so that it may be rotated as well as gyrated so as to carry the work pieces through an irregular path between the opposed lapping wheels. As illustrated in the drawings, a rotatable cage 110 is provided with a peripheral gear 111. The cage 110 is preferably supported by a plurality of rotatable gears 112, 113, 114 and 115 which mesh with the gear 111 and are supported to rotate with shafts 116, 117, 118 and 119. Each of the shafts or studs 116, 117, 118 and 119 is mounted eccentric to its axis of rotation and is in turn supported on positively rotated shafts 120, 121, 122 and 123 and is rotated synchronously so as to rotate and revolve the gears 112, 113, 114 and 115 so as to transmit a rotary movement through gear 111 to cage 110 while gyrating the cage in an irregular path. The mounting and drive for each of the shafts 120, 121, 122 and 123 are identical, consequently only one of the drives has been illustrated in detail. The shaft 121 is provided with a relatively long pinion or sprocket 130 which is connected by a link chain 131 with a gear or sprocket 132 (Fig. 6) mounted on the shaft 120 which is rotatably supported in a projection 134 of the base 10. The stud 116, which rotatably supports the gear 112, serves as a crankpin and is adjustably mounted on a rotatable plate 135 which is mounted on the end of the shaft 120. The plate 135 is provided with a T-slot 136 which serves to facilitate adjustment of the stud or crankpin 116. The pin 116 may be adjusted to the required extent relative to the axis 50 60 65 70 75 80 85 90 95 100 105 110 115 120 125 130 135 140 145 150 155 160 165 170 175 180 185 190 195 200 205 210 215 220 of rotation of the shaft 128 and may be clamped in adjusted position by means of a nut 131. In order to drive the crankpin 119 in synchronism with the pin 116, a gear or sprocket 140 is mounted on the shaft 120 and is connected by a link chain 141 with a gear or sprocket 142 which is keyed to the shaft 123 so as to rotate the shaft 123 and revolve the crankpin 119 in synchronism with the crankpin 116.

10 Similarly, the sprocket or pinion 130 is connected by a link chain 144 which is arranged in a similar manner to rotate the shaft 121. The details of the mounting of the shaft 121 and crankpin 117 have not been illustrated since this 15 construction is identical with the mounting of the shaft 120 and the crankpin 116. The shaft 121 is provided with a gear or sprocket (not shown) which is connected by a link chain 145 with a gear or sprocket 146 on the rotatable shaft 122 20 and serves to revolve the crankpin 118 in synchronism with the crankpin 117.

All of the crankpins 116, 117, 118 and 119 are 25 adjustably mounted on rotatable plates so that they are offset by the same amount from the axis of rotation of their supporting shafts 120, 121, 122 and 123, respectively. The crankpins 116, 117, 118 and 119 are all revolved in the same direction and their movements are synchronized due to the link chain drive above described. This 30 driving mechanism serves to gyrate the cage as it is rotated by the gear 111.

In order to facilitate loading and removal of work pieces from the machine, two sets of adjustably mounted work holders are provided on the 35 cage 110. These work holders are preferably arranged in pairs, that is so that alternate work holders are in an operative and inoperative position so that after a set of work pieces have been lapped to the desired extent, the lapped work 40 pieces may be readily and simultaneously removed to an inoperative position while at the same time a set of new pieces of work to be lapped are moved into an operating position between the lapping wheels 11 and 12.

45 The cage 110 is provided with a plurality of slides 150 which are supported in slideways 154 on the cage 110 and are arranged to move in a substantially radial path. The slides 150 are shown in an operating position and carry a work 50 piece, such as a piston rod 151, within a work carrier 152 which is fixedly mounted on the slide 150. The work piece or piston rod 151 is held in the desired location on the slide 150 by means of a locating pin 153. The cage 110 similarly supports 55 a plurality of corresponding slides 160 which are mounted in slideways 164 on the cage 110. The slides 160 are each provided with work holders 162 having locating pins 163 arranged to receive, support and locate a plurality of work pieces, such 60 as piston rods 161, for a lapping operation.

During the lapping of the piston rods 151, the cage 110 is rotated and gyrated to carry the piston rods 151 through an irregular path between the opposed operative faces of the lapping wheels 65 11 and 12. During this lapping operation, the cage 110 rotates slowly and as it rotates, the new pieces of work, such as piston rods 161, may be positioned on the idle set of slides 160 as the cage 110 rotates so that when the piston rods 70 151 have been lapped to the desired extent, they may be readily removed from operative relation with the wheels and the new set of piston rods 161 may be simultaneously inserted in operative relation therewith.

75 In order to facilitate movement of the two sets

of slides 150 and 160 to and from an operating position, the side faces of the slides are provided with rack teeth 170 and 171 which mesh with opposite sides of a pinion 173. The pinion 173 is fixedly mounted on a rotatable shaft 174. When it is desired to move the work carrying slide 150 to an inoperative position after a lapping operation, it is merely necessary to rotate the shaft 174 in a clockwise direction, as indicated in Figure 3, which serves to move the slide 150 downwardly to an inoperative position and serves to simultaneously move the slide 160 upwardly into an operative position between the lapping wheels 11 and 12.

Each of the pairs of slides 150 and 160 is constructed in the same manner as shown in Figs. 3 and 4 and as above described. Details of construction of each individual slide operating mechanism have not been illustrated, since this is not believed to be necessary. Each of the pairs of slides may be operated individually, if desired.

In order, however, to facilitate rapid production, it is desirable to provide means for simultaneously rotating all of the shafts 174 so that the gears 173 will be synchronously rotated to simultaneously withdraw all of the set of slides 150 to an inoperative position while simultaneously moving the set of slides 160 and work pieces 161 into an operating position between the lapping wheels 11 and 12.

This is preferably accomplished by providing a gear 180 (Figs. 1 and 4) fixedly mounted on the end of each of the shafts 174, as indicated in Figs. 1 and 4. The gears 180 all mesh with an internal ring gear 181 which rotatably fits within an internal cylindrical aperture 182 in the cage member 110. By rotating the internal ring gear 181, all of the gears 180 may be simultaneously and synchronously rotated to move the set of work slides 150 to an inoperative position after a predetermined lapping operation while simultaneously moving a set of slides 160 and a new set of work pieces 161 into operative position.

The periphery of a flange 183 is provided with a plurality of holes 184 into which a pin or rod may be inserted to facilitate turning of the ring gear 181 relative to the cage 110.

It is desirable, after a loading operation has been completed, to lock the ring gear 181 relative to the cage 110. This is preferably accomplished by means of one or more clamping screws 185 (Fig. 4) which pass through elongated slot or slots 186 in the flange 183 of the internal gear 181 and are screw threaded into a portion of the cage 110. After the slides have been adjusted into the desired operating position, the bolt or bolts 185 may be tightened to lock the internal ring gear 181 relative to the cage 110 and the lapping operation on the new pieces of work may then proceed.

The operation of this mechanism will be readily apparent from the foregoing disclosure. A series of work pieces 151 are loaded into operating position on the slides 150 and are moved into operative position between the lapping wheels 11 and 12. The lapping wheels 11 and 12 are then adjusted manually by means of the hand wheels 97 and 99, and the reverse valve 107 is positioned to admit fluid under pressure simultaneously through pipes 77 and 87 to move the lapping wheels towards each other to engage the opposite side faces of the work piece to be lapped. The pressure admitted through the pipes 77 and 87 is regulated by means of a well-known pressure regulating valve (not shown). The lapping opera-

tion may then be started by moving the clutch operating lever 60 to engage the clutch 39 and start the simultaneous rotation of the lapping wheels 11 and 12 in the opposite direction and at 5 the same time start a rotary and gyrating movement to the cage 110. The lapping operation proceeds until the work pieces 151 have been lapped to the desired extent. The valve 101 controlling the admission of fluid is then shifted to 10 admit fluid under pressure through pipes 79 and 88 to separate the lapping wheels 11 and 12. The clutch operating lever 60 is then shifted to disengage the clutch and to facilitate removal of the lapped pieces of work. The bolt or bolts 185 15 are then unclamped and by means of a pin inserted in one of the holes 184, the ring gear 181 may be rotated relative to the cage 110 to simultaneously move all of the slides 150 to an inoperative position while simultaneously moving all 20 of the set of slides 160 into an operative position, presenting a new set of work pieces 161 into operative relation with the lapping wheels 11 and 12. The ring gear 181 may then be locked in adjusted position by tightening the clamping bolts 185 and 25 the lapping operation on the new set of work pieces may then proceed.

It will thus be seen that there has been provided by this invention apparatus in which the various objects hereinabove set forth together 30 with many thoroughly practical advantages are successfully achieved. As many possible embodiments may be made of the above invention and as many changes might be made in the embodiment above set forth, it is to be understood that 35 all matter hereinbefore set forth or shown in the accompanying drawings is to be interpreted as illustrative and not in a limiting sense.

We claim:—

1. A lapping machine comprising a pair of opposed relatively rotatable lapping wheels, means to relatively rotate said lapping wheels, a work carrying cage arranged to simultaneously support a plurality of work pieces in operative relation with said lapping wheels, means to rotate and 45 gyrate said cage to carry the work pieces through an irregular path between said wheels, and means to simultaneously move said wheels towards or from each other.

2. A lapping machine comprising a pair of opposed relatively rotatable lapping wheels, means to relatively rotate said lapping wheels, a work carrying cage arranged to simultaneously support a plurality of work pieces in operative relation with said lapping wheels, means to rotate and 55 gyrate said cage to carry the work pieces through an irregular path therebetween, and means including a fluid pressure system arranged to move said laps simultaneously into operative engagement with said work pieces for a lapping operation.

3. A lapping machine comprising a pair of opposed relatively rotatable lapping wheels, means to relatively rotate said lapping wheels in opposite directions, a work carrying cage arranged to simultaneously support a plurality of work pieces in operative relation with said lapping wheels, means to rotate and gyrate said cage to carry the work pieces through an irregular path between said wheels, and means including a piston and 65 cylinder operatively connected to simultaneously move each of said wheels into operative relation with the work pieces for a lapping operation.

4. A lapping machine comprising a pair of opposed relatively rotatable lapping wheels, 70 means to relatively rotate said lapping wheels, a

work carrying cage arranged to simultaneously support a plurality of work pieces in operative relation with said lapping wheels, means to rotate and gyrate said cage relative to said lapping wheels to carry the work pieces through an irregular path therebetween, means including a fluid pressure operated piston and cylinder associated with each of said wheels, and means to simultaneously admit fluid under pressure to each of said cylinders to cause the lapping wheels to simultaneously move into or away from operative position with relation to the work pieces to be lapped.

5. A lapping machine comprising a pair of opposed relatively rotatable lapping wheels, means to relatively rotate said lapping wheels in opposite directions, means to simultaneously move said wheels toward and from each other, a work carrying cage arranged to simultaneously support a plurality of sets of alternate work pieces, one of said sets of alternate work pieces being simultaneously in an operative position with relation to said wheels while the other set of alternate work pieces is in an inoperative or loading position, and means to simultaneously move one set of the work pieces from a lapping position after a predetermined lapping operation and to simultaneously present another set of work pieces for a lapping operation.

6. A lapping machine comprising a pair of opposed relatively rotatable lapping wheels, means to relatively rotate said wheels in opposite directions, means to simultaneously move said wheels toward and from each other, a work carrying cage, means to move said cage through an irregular path between said wheels, means including a plurality of movable work carrying slides on said cage, and means to simultaneously move said slides relative to the cage member to move work pieces to and from an operating position.

7. A lapping machine comprising a pair of opposed relatively rotatable lapping wheels, means to relatively rotate said wheels in opposite directions, means to simultaneously move said wheels toward and from each other, a work carrying cage, means to move said cage through an irregular path between said wheels, a plurality of pairs of work supporting slides slidably mounted on said cage, alternate slides being arranged to support work pieces in operative relation with said wheels for a lapping operation while the other slides are in an inoperative or loading position, and means to simultaneously shift the two sets of slides to move the first named slides to an inoperative position after a predetermined lapping operation while moving the second named slides into an operating position to present a new set of work pieces for a lapping operation.

8. A lapping machine comprising a pair of opposed relatively rotatable lapping wheels, means to relatively rotate said wheels in opposite directions, a work carrying cage arranged to simultaneously support a plurality of work pieces in operative relation with said lapping wheels, means to rotate and gyrate said cage to carry the work pieces through an irregular path therebetween, means including a fluid pressure operated piston and cylinder associated with each of said wheels to move the wheels simultaneously toward and from each other, and manually operable means for independently adjusting the path of movement of each of said wheels.

9. A work carrying cage for a lapping machine comprising a rotatable cage member, a plurality

of pairs of work supporting slides on said cage, alternate slides being arranged to support work pieces in operative relation with said wheels for a lapping operation while the other slides are in an inoperative or loading position, and means to simultaneously shift said slides from an operative position to an inoperative position after a set of work pieces have been lapped to the predetermined extent.

10. 10. A work carrying cage for a lapping machine comprising a rotatable cage member, a plurality of pairs of work supporting slides on said cage which are arranged to move in a substantially radial direction, alternate slides being arranged to support work pieces in operative relation with said wheels for a lapping operation while the other slides are in an inoperative or loading position, and means to simultaneously shift all of said slides to move the first named slides to an inoperative position after a predetermined lapping operation while moving the second named slides into an operating position to present a new set of work pieces for a lapping operation.

11. 11. A work carrying cage for a lapping machine comprising a disk shaped cage member, a gear formed on the periphery of said cage member, a

plurality of rotatable gears which mesh with said gear on the cage, means to simultaneously rotate and revolve said gears to carry said cage member through an irregular path, and means to support a plurality of work pieces in position for a lapping operation, and readily accessible means to remove said work pieces to an inoperative position after a lapping operation has been completed.

12. 12. A work carrying cage for a lapping machine comprising a disk shaped cage member, a gear formed on the periphery of said cage member, a plurality of rotatable gears meshing with said gear on said cage, means to simultaneously rotate and revolve said gears to carry said cage member through an irregular path, a plurality of work carrying slides which are movable radially on said cage member to support a plurality of work pieces in position for a lapping operation, and means to simultaneously move said slides relative to said cage member to move said work pieces to an inoperative position after a predetermined lapping operation has been completed.
